CLAIM

We claim the ornamental design for a remote control, as shown and described.

DESCRIPTION

FIG. 1 is a perspective view of a remote control showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is an enlarged view of the joysticks bumpers textured portion called out in FIG. 1; and,

FIG. 9 is an enlarged view of the rotary dial bumpers textured portion called out in FIG. 6.

The broken line showing of the Remote Control is for the purpose of illustrating portions of the article that forms no part of the claimed design. The broken line in FIGS. 1 and 6 demarcating the textured elements are for purposes of annotation and form no part of the claimed design.
